UNITED STATES PATENT OFFICE.

BENJAMIN F. WOODING, OF MONTCLAIR, NEW JERSEY.

RAILROAD-TRAFFIC-CONTROL EQUIPMENT.

1,211,995.

Specification of Letters Patent.

Patented Jan. 9, 1917.

Application filed November 9, 1915. Serial No. 60,605.

To all whom it may concern:

Be it known that I, BENJAMIN F. WOODING, a citizen of the United States, and a resident of Montclair, in the county of Essex and State of New Jersey, have invented a new and Improved Railroad-Traffic-Control Equipment, of which the following is a full, clear, and exact description.

Among the principal objects which the present invention has in view are: to provide a railway road-bed with traffic control apparatus capable of avoiding tools, such as snow-plows, for clearing the road-bed, and for avoiding other members carried by the locomotives or trains purposely or accidentally pendent therefrom in the path of said control apparatus; to provide characterization current-supplying ramps resiliently suspended in an operative position to be readily depressed therefrom when struck by a moving object; and to provide a suspension mechanism for the above-mentioned ramps, which is simple and durable and readily replaced.

Drawings.—Figure 1 is a top plan view showing a fragment of a railway road-bed and a control ramp having an equipment apparatus constructed and arranged in accordance with the present invention; Fig. 2 is a side view of the same, showing in conjunction therewith, a railway car wheel and a contact blade mounted thereon for coöperation with said equipment apparatus; Fig. 3 is a cross section on an enlarged scale, the section being taken as on the line 3—3 in Fig. 1, showing the equipment apparatus in its service position, part of said apparatus being cut away to show the supporting spring therefor; Fig. 4 is a similar view showing the apparatus in a depressed position; Fig. 5 is a detail view on an enlarged scale, in section, the section being taken as on the line 5—5 in Fig. 1, the co-operative parts of the apparatus being shown in their inactive position; Fig. 6 is a similar view, showing the parts in their active position and a contact blade as extending therebetween; Fig. 7 is a detail view in cross section, showing a mounting for said contact blade and contact member coöperating therewith for supplying current to the moving element of the railway system for controlling the same; Fig. 8 is a diagrammatic view showing the contact blade, the engagement thereof with a frag-

ment of a control apparatus, and a portion of the operating control mechanism carried by the moving elements of the railway system; Fig. 9 is a side view, partly in section, of a suspension structure for the control device, said structure being in accordance with a modification of the invention.

Description.—As seen in the drawings, the railway road-bed has disposed at the side thereof, ramps, which are suspended by arms 14, the outer ends whereof are united rigidly by bracket blocks 15 and bolts 16, to an angle rail 17, as best seen in Figs. 3 to 6, inclusive. The blocks 15 are properly insulated from the arms 14, so that track current supplied to the ramps by means of a terminal 18, as shown in Fig. 1 of the drawings, is not grounded on the track rail upon which the arms 14 are pivotally mounted. The arms 14 are each provided with a foot extension 19 to pass below the track rail and to extend therebeyond to receive a retaining block 20, which has a supporting lip 21, and which is held in position by a bolt and nut 22. Below the lip 21 and coöperating therewith, is formed in the foot 19, a recess 23, into which the flange of the rail extends when the arm 14 is depressed, as seen best in Fig. 4 of the drawings. The arms 14 are normally suspended and maintained in service position as shown in Fig. 3 of the drawings, by means of heavy coil springs 24 with which the arms are equipped. Each spring 24 is mounted under tension between rocking blocks 25 and 26, the latter of which has an angular recess 27 to form a seat for the block upon the outer edge of the flange of the railway rail, and thereby form a rocking seat for pivoting said block and spring structure connected therewith. The block 25 has a centrally disposed nib 28 for seating within a perforation 29 formed as a socket therefor in a bearing bracket 30, which is preferably integrally constructed with the arm 14. The blocks 25 and 26 are each furnished with conventional centering pins 31 for holding the spring 24 in service relation to the said blocks.

It is obvious that the weight of the ramp supported at the outer ends of the arms 14, is carried by the springs 24. Provision is made for determining the service position of the ramps and of the rails 17 thereof, by using stop plates 32, which are held on the

arms 14 by screws 33, and in adjusted relation thereto. The inner ends of the plates 32 engage the railway rail and preferably at the junction of the head with the web thereof, as best seen in Fig. 3 of the drawings.

It is obvious that when the railway road-bed is equipped with ramps having rails 17 normally held in service in a plane above the railway rails, the ramps may be depressed below the crown of the rails, as shown best in Fig. 4 of the drawings, whenever a heavy object, such as a snow-plow or other track-clearing or construction instrument, is moved over the road-bed at a level with or below the plane of the top of the railway rails. When the ramps are so depressed, the arms 14 swing on the inner edges of the flange of the railway rail with which they are engaged, the pivot connection being formed by the blocks 20 and clips 21 thereof. The normal angular disposition of the opposite edge of the flange of the railway rail and the brackets 30, results in the compression of the springs 24 when the brackets are moved toward the plane of the railway rail flange. When the pressure on the rails 17 is removed, the springs 24 immediately rock the arms 14 to replace the ramps in the service position. The resistance of the springs 24 is sufficient to hold the ramps in their normal service position under normal service conditions.

The herein-described ramps are provided for transmitting electric current from an outside source, such as indicated by the numeral 34, shown in the diagram in Fig. 8 of the drawings, and by means of the terminal 18, likewise indicated in said Fig. 8, and as also seen in Fig. 1. The source 34, in practice, is a power station supplying current for a stretch of track or railway road-bed, and thus in circuit with one or more of the ramps and with the rails 17 thereof. The contact thus normally established is due to the lift of the arms 14 and rails 17 connected therewith, and the hooks 35 dependent from the rails 17 and extended under to form a contact with the angular brackets 36. This arrangement is best seen in Fig. 8 of the drawings. Thus, each of the ramps is normally charged with an electric current for saturating the magnet 37 with which each moving member of the railway system is provided. The magnet 37 is disposed in the metallic circuit embodying the contact blade 38, local wires 39 and 40, and a master switch 41.

As seen in Fig. 8 of the drawings, the wire 40 is grounded and one side of the source 34 is also grounded. Therefore, when the switch 41 is closed and the blade 38 is in contact with the ramp, the circuit incorporating the source 34 and magnet 37 is completed. When the magnet 37 is thus

saturated, an armature cap 42 is drawn toward the magnet to seat the ball valve 43 relied upon to close the escape pipe 44 of an air brake system with which the moving member is provided. Normally, or when the blade 38 is not engaged by the ramp, said blade is rocked by the spring 45 to a position where the finger 46 makes contact with the yielding terminal 47. The terminal 47, together with the wires 48, 49, an electric source 50, the blade 38, wire 39, switch 41, and wire 40, form a second circuit by which the magnet 37 is energized, with the effect that the armature 42 and ball valve 43 are seated. In other words, it is necessary that both circuits, that incorporating the source 34 and that incorporating the source 50, shall be open at the same time to deenergize the magnet 37 and permit the air pressure on the ball valve 43, with the result that the air pressure in the train pipe with which the moving member is provided, is reduced.

As is shown best in Fig. 1 of the drawings, the ramps are incorporated in a distinct circuit and in series therewith. That is to say, the rail 17 is connected with the main line 51 at both ends of the ramp, by means of the terminals 18. It will also be understood that the source 34 is controlled by traffic conditions prevailing in the block ahead. Therefore, if it so happens that a moving member passes a ramp, which for any reason is not charged with current, when the blade 38 is moved to the position shown in Fig. 8 of the drawings, the magnet 37 is deenergized due to the opening of the circuit incorporating the source 50 which is carried by the moving member. When the air from pipe 44 lifts the armature 42, the exposed area of the said armature is sufficiently great to prevent the magnet 37 re-seating the ball valve 43, the power of the magnet being less than that of the escaping air. It is not until sufficient air has escaped through the pipe 44 to reduce the pressure below the force of the magnet, that the engineer is permitted to charge the train pipe for reestablishing the working pressure thereof. In this manner the operation of the circuit incorporating the source 50, is offset, when the blade 38 having passed from the control of the ramp is again rocked to the position where the finger 46 rests on the terminal 47 and the magnet 37 becomes saturated in consequence thereof.

From the foregoing it will be seen that when the traffic condition of the block ahead is such as to cut out the supply of current to the rearward ramp, the moving member endeavoring to pass such ramp will be brought to a stop without the intervention of the engineer or person in charge.

As shown best in Fig. 6, the blade 38 when engaged by the ramp is held against

the electrically charged rail 17, by an auxiliary rail 52. The rail 52 is normally held, as seen in Figs. 3 and 4 of the drawings, under, or in closed relation to the rail 17, 5 being held in this position by springs 53 and bolts 54, which surround the same. The rail 52 is pivotally connected with the rail 17 by means of hanging brackets 55 and 56, said brackets being pivotally united by pins 10 57. The housing 58, wherein each spring 53 is disposed, is integrally formed in the brackets 56, as shown best in Figs. 5 and 6 of the drawings. The springs 53 and bolts 54 are constructed to permit the necessary 15 movement of the rail 52 when yielding to the blade 38, as seen in Fig. 6 of the drawings.

As shown in Figs. 1 and 2 of the drawings, the ramps composed of the rails 17 and 52, are spread or flared at the ends of said ramps to form entranceways 59, and are depressed at the terminals of said entranceways below the normal path of the blades 38. The rail 17 of each ramp is 25 structurally connected with an anchor member 60 at opposite ends of the ramp, and by means of an insulating block 61. As seen best by comparison of Figs. 1 and 2 of the drawings, the widest portion of the entranceways 59 is likewise the highest portion of the ramp. By this means is insured the entrance of the blades 38 between the rails 17 and 52.

In Fig. 9 of the drawings, a modified form of the arms employed for supporting the ramps is shown. The modification consists principally in that there are substituted for the extensions 19, bed plates 62, which are bolted directly to the ties of the road-bed. The springs 24 employed therein are also supported at the lower or inner end by a second rocking block 25 in lieu of the rocking block 26. The rocking block 25 thus substituted has a seat in a fin 63 with which said bed plate is provided. The bed plate 62 and arm 64 of the modified form are pivotally connected by a pivot pin 65. The operation of the modified form corresponds in all essentials with the operation of the preferred form, with the exception that the limit of the elevation of the ramp is controlled in the modified form by the jointed links 66 and 67. The link 66 is pivotally united by a bolt 68 with the arm 64, while the link 67 is similarly united by a bolt 69 with the bed plate 62. The link 67 is furnished with an overturned end or toe 70, thus shaped to operate as a stop member to engage the end of a set screw 71. It is obvious that in accordance with the manipulation of the screw 71, the links 66 and 67 are limited or regulated in their relative opening or movement and in turn limit or regulate the elevation of the ramp and the rail 17 thereof above the bed plate 62 and

the railway tie on which said bed plate is mounted.

Claims:

1. An equipment as characterized comprising a ramp; and vertically yielding supports for said ramp permitting the depression of the same below the crown of the track rail with which said ramp is associated. 70

2. An equipment as characterized comprising a ramp; vertically yielding supports for said ramp permitting the depression of the same below the crown of the track rail with which said ramp is associated; and means pivotally connecting said supports 80 with the adjacent track rail. 75

3. An equipment as characterized comprising a ramp; vertically yielding supports for said ramp permitting the depression of the same below the crown of the track rail 85 with which said ramp is associated; and means pivotally connecting said supports with the adjacent track rail, said means embodying foot extensions disposable below the flange of said rail, and a retaining block 90 removably connected therewith forming a pivot seat for the inner edge of said flange. 90

4. An equipment as characterized comprising a ramp anchored upon a road-bed; a plurality of supporting arms rigidly secured to said ramp intermediate the ends thereof, said arms being provided each with a foot extension for disposition below the flange of an adjacent track rail and having a hook-like pivot seat for engaging the inner edge thereof; and a plurality of spiral springs for supporting said arms, said spring being pivotally connected at the ends thereof with one of said arms and the edge 100 of said flange. 105

5. An equipment as characterized comprising a ramp anchored upon a road-bed; a plurality of supporting arms rigidly secured to said ramp intermediate the ends thereof, said arms being provided each with 110 a foot extension for disposition below the flange of an adjacent track and having a hook-like pivot seat for engaging the inner edge thereof; a plurality of spiral springs for supporting said arms, said springs being 115 pivotally connected at the ends thereof with one of said arms and the edge of said flange; and means for definitely arresting the upward movement of each of said arms. 120

6. An equipment as characterized comprising a ramp anchored upon a road-bed; a plurality of supporting arms rigidly secured to said ramp intermediate the ends thereof, said arms being provided each with a foot extension for disposition below the 125 flange of an adjacent track rail and having a hook-like pivot seat for engaging the inner edge thereof; a plurality of spiral springs for supporting said arms, said springs being pivotally connected at the ends thereof with 130

one of said arms and the edge of said flange, a stop member adjustably mounted on each of said arms; and means for fixing the operative position of said member for determining the elevation of said ramp.

7. An equipment as characterized comprising a ramp; vertically yielding supports for said ramp permitting the depression of the same below the crown of the track rail with which said ramp is associated; means pivotally connecting said supports with the adjacent track rail; and means for supplying electric current to said ramp when actively disposed.
10. An equipment as characterized comprising a ramp; vertically yielding supports for said ramp permitting the depression of the same below the crown of the track rail with which said ramp is associated; means pivotally connecting said supports with the adjacent track rail; means for supplying electric current to said ramp when actively disposed; and means for discontinuing said supply when said ramp is depressed.
15. An equipment as characterized comprising a ramp; vertically yielding supports for said ramp permitting the depression of the same below the crown of the track rail with which said ramp is associated; means pivotally connecting said supports with the adjacent track rail; means for supplying electric current to said ramp when actively disposed; and means for discontinuing said supply when said ramp is depressed.
20. An equipment as characterized comprising a ramp; vertically yielding supports for said ramp permitting the depression of the same below the crown of the track rail with which said ramp is associated; means pivotally connecting said supports with the adjacent track rail, said means embodying a definitely positioned bracket connected with the road-bed structure; and a hook for engaging

said bracket, said hook being rigidly attached to said ramp.

10. An equipment as characterized comprising a plurality of ramps, each having pivotally mounted interlocking rails; yielding means for normally holding said rails in folded position; means for guiding a blade between said rails for receiving electric current therefrom; a supply of electric current to said rails; and a plurality of yielding supports pivotally connecting said ramps to the adjacent rails in fixed relation thereto.

11. An equipment as characterized comprising a plurality of ramps, each of said ramps comprising a plurality of edge-lapping rails; and resilient means for maintaining said rails in normal relation, said rails being longitudinally shaped to form at the ends of said ramps, flared entranceways between said rails, the ends of said rails forming said entranceways being depressed relative to the normal height of said ramps, and said rails extending above the normal height of said ramps at the widest section of said entranceways for insuring the engagement by said rails, of a contact member with which the moving members of a railway system is provided.
